MOVING COIL INSTRUMENT WITH STRETCHED STRIP SUSPENSION

Friedrich Endlich, Langen in Hessen, and Walter Hufbauer, Frankfurt am Main, Germany, assignors to Hartmann & Braun Aktiengesellschaft, Frankfurt am Main, Germany, a corporation of Germany

Application March 3, 1953, Serial No. 340,018

Claims priority, application Germany March 8, 1952

12 Claims. (Cl. 317—168)

This invention relates to an electrical measuring instrument employing a moving coil being suspended between two taut strips, enclosing a core and moving in a magnetic field. Such taut suspensions provide the strips to be stretched by means of springs. These springs are also supposed to absorb shocks elastically to which the instrument is exposed. Provisions must be made, however, that the movements of the coil due to the taut suspension be limited, because otherwise a too high stress will occur in the taut strips and thus result in a rupture. In the direction of the axis of rotation the core represents a limit because the front side of the moving coil fits to the front side of the core. Such a limit vertically to the moving coil, however, does not exist in any case and must specially be provided for in order to prevent the movements of the coil to become too violent in this direction.

The invention specially relates to the arrangements of stops limiting the movement of the coil in the vertical direction to its plane. The invention avoids a high degree additional components for the construction of these stops and thus quite a simple design is possible necessitating no further space.

The invention provides guide parts at the moving coil which with some clearance protrude into recesses at the front side of the core. These recesses limit the lateral movement of the coil, the guide parts being fastened at the moving coil and variable with regard to their position, so that the moving coil can be pushed over the core and the guide parts inserted in the recesses.

Another possibility would be to fasten tightly the guide parts at the coil and to provide the core with additional recesses where the guide parts are able to pass through when pushing the moving coil over the core. This done, the recesses can be closed if required.

Examples of the invention are shown by the relevant figures.

Figs. 1 and 2 show the invention with regard to a core magnet system, i. e. Fig. 1 shows a vertical sectional view and Fig. 2 the view from above.

Figs. 3 and 4 show another construction also as sectional view and from above.

Figs. 5 and 6 show a design where additional recesses are provided in the core and where the guide parts are inserted.

In Figs. 1 and 2 the core is marked with 1 and around which the moving coil 4 turns. The moving coil 4 suspended between two stretched strips 3 which are tightened by the leaf springs 14. 9 stands for the pointer. The strips 14 are held by a support 15 fastened to the external ring shaped yoke 16 which are both fastened to the core 1. The example shows a so-called core magnet system where the internal core 1 is to be the permanent magnet, that means of permanent-magnet material, and where externally a ring shaped yoke 16 consisting of soft iron is provided.

The invention, however, is likewise applicable for a system with external magnet, that means where core 1

2

consists of soft iron and where at the external side the pole pieces of for instance a U-shaped permanent magnet generate the magnetic field.

There are two cylindrical recesses 2 provided at the front sides of the core. When manufacturing the core for instance which is often accomplished by means of moulding, these recesses can already be made during this stage of manufacturing. At the internal front sides of the moving coil two thin metal plates 5 and 5' of non-magnetic material are fastened. The latter are stretched before mounting the system as shown by the upper plate 5. After having pushed the moving coil over the core, both free ends of this little plate are bent into the recess of the core as illustrated below by 5'. They must be a size that these recesses are just filled with some clearance. These guide parts are meant to be the stops for the movement of the coil. If the coil is moved in the direction of the arrow, i. e. vertically to its plane, the bent down ends of the guide parts hit upon the internal edge of the recess and thus limit the movement.

A second possibility is to use elastic material for the plates 5 and to bend down their ends already before mounting. When pushing the moving coil over the core, these plates are bent back until the core can be slipped over easily and then engage without any help in the recesses 2 of core 1. In this case both guide parts act simultaneously as an elastic stop for movements of the coil in the direction of the axis of rotation.

Another design is illustrated by Figs. 3 and 4 where the fastening of the stretched strips and the external part of the magnetic circuit are omitted in order to simplify the illustration. Again the moving coil is marked with 4 and the core with 1, the stretched strips with 3. The pointer 9 is extended beyond its fastening at the moving coil and represents itself the guide part. For this purpose the pointer is bent down at 8 and engages in a circular recess 7 in the core. The protruding end of the pointer simultaneously carries the counterweight 10. If the recess in the core is provided for accordingly it can act simultaneously as stop for limiting the deflection.

Figs. 5 and 6 show another solution where the insertion of the guide parts is rendered possible by additional recesses in the core. The same symbols are again chosen for core, support, stretched strips etc. as in Figs. 1 to 4. Again a cylindrical recess is provided in the core as in Figs. 1 and 2. In addition, however, there is recess 12 resembling a narrow slot. Through this slot the guide parts can be inserted which in this case are fixed inelastically at the coil. If this slot should prove to be inconvenient it can be closed subsequently by some suitable part. The present case shows an example where it is not necessary to close this slot. The guide parts are made of two springs 11 which in their normal condition are spread out like a fan. They are pressed together when the support is inserted and can thus be led through the guiding slot. They then spread out within the cylindrical part and act as stops for limiting lateral movements.

60 We claim:

1. A measuring instrument having a moving coil, a core, a pair of strips and springs, the coil being fixed to the two strips stretched by the springs, said coil turnable around the core, guide parts fixed to the coil, a face of said core having a recess, the guide parts having ends protruding into said recess, said recess being shaped so as to allow the protruding ends of the guide parts to move in their orbits but having only a clearance in radial direction smaller than the least distance in radial direction occurring between the coil and any other part of the instrument.

2. A measuring instrument as in claim 1, the material of said guide parts being of such kind as to allow deformation.

3. A measuring instrument as in claim 2 said material being elastic.

4. A measuring instrument having a moving coil, a core having an end face, the core having a recess in the zone of the end face, a pair of strips and springs, the moving coil being fixed to the two strips and stretched by the springs, said coil being turnable around the core, guide parts fixed to the coil, said guide parts consisting of sheet metal strips the ends of which are bent, the bent ends of the sheet metal strips being turnable in orbits about the axis on which the coil turns and protruding into the recess, said recess being shaped so as to allow the protruding ends of the guide parts to move in their orbits freely in an angular direction about said axis, but having walls near to said orbits and ends, the clearance between the ends and the walls in a radial direction being smaller than the least distance in radial direction occurring between the coil and any other part of the instrument.

5. A measuring instrument having a moving coil, a core, springs and a pair of strips, the coil being fixed to the two strips stretched by the springs, said coil being turnable around the core, guide parts fixed to the coil and having ends movable in arcuate orbits as the coil is turned, an end face of said core having a recess, said ends protruding into the recess, the recess and walls thereof being shaped so as to allow the protruding ends of the guide parts to move in their orbits but having a radial clearance from the walls smaller than the least distance in radial direction occurring between the coil and any other part of the instrument, said core having in addition a radial slot shaped so as to allow the guide parts to pass radially into the recess when the coil is slipped over the core.

6. In a moving coil instrument, a base; separated spring mounting prongs on and projecting in a common direction from the base; a cylindrical core of magnetic material between the prongs, and fast with respect to the base, and provided at one end with a recess having arcuate walls coaxial with the core and open toward one of the respective prongs; a movable coil around the core and each end thereof and adapted to oscillate about the axis of the core; a pair of strips each lying substantially along the axis of the core and normally in a common plane, each strip having one end portion secured to one prong and the other to the coil to provide a torsion suspension for the coil to oscillate about said axis; and a detent member secured in fixed relationship to the coil adjacent said one end of the core and projecting into the recess clear of the walls thereof and so near the walls that the detent member prevents radial motion of the coil to a predetermined degree.

7. In a moving coil instrument, a base; separated spring mounting prongs on and projecting in a common direction from the base; a cylindrical core of magnetic material between the prongs, and fast with respect to the base, and provided at each end with a cylindrical recess coaxial with the core and open toward the respective prongs to provide a projecting annular flange, a movable coil around the core and each end thereof and adapted to oscillate about the axis of the core; a pair of strips each lying substantially along the axis of the core and normally in a common plane, each strip having one end portion secured to one prong and the other to the coil to provide a torsion suspension for the coil to oscillate about said axis; and detent members secured fast to the inner portion of the coil adjacent the end faces of the core and projecting into the respective recesses clear of the inner walls of the flange and so near the walls that the detent members prevent radial motion of the coil to a predetermined degree.

8. In a moving coil instrument, a base; separated spring mounting prongs on and projecting in a common direction from the base; a cylindrical core of magnetic material between the prongs, and fast with respect to the base, and provided at one end with an arcuate recess having arcuate walls coaxial with the core and open toward one of the respective prongs; a tubular flux conductor of magnetic material fixed on the base and coaxial with and surrounding the core and spaced therefrom, a movable coil around the core and each end thereof and adapted to oscillate about the axis of the core in the annular space between the conductor and core; a pair of strips each lying substantially along the axis of the core and normally in a common plane, each strip having one end portion secured to one prong and the other to the coil to provide a torsion suspension of the coil to oscillate about said axis; and a detent member secured fast with respect to the coil adjacent the said one end of the core and projecting into the recess clear of the walls thereof and so near the walls that the detent member prevents radial motion of the coil to a degree sufficient to prevent the coil from coming into contact with the core and conductor.

9. In a moving coil instrument, a base; separated spring mounting prongs on and projecting in a common direction from the base; a cylindrical core of magnetic material between the prongs, and fast with respect to the base, and provided at each end with a cylindrical recess coaxial with the core and open toward the respective prongs to provide a projecting annular flange; a tubular flux conductor of magnetic material on the base and coaxial with and around the core and spaced therefrom, a movable coil around the core and each end thereof and adapted to oscillate about the axis of the core in the annular space between the conductor and core; a pair of strips each lying substantially along the axis of the core and normally in a common plane, each strip having one end portion secured to one prong and the other to the coil to provide a torsion suspension for the coil to oscillate about said axis; and detent members secured fast to the inner portion of the coil adjacent the end faces of the core and projecting into the respective recesses clear of the walls thereof and so near the walls that the detent members prevent radial motion of the coil to a degree sufficient to prevent the coil from coming into contact with the core and conductor.

10. In a moving coil instrument, a base; separated spring mounting prongs on and projecting in a common direction from the base; a cylindrical core of magnet material between the prongs, and fast with respect to the base, and provided at one end with a cylindrical recess coaxial with the core and open toward one of the respective prongs to provide a projecting annular flange; a tubular flux conductor of magnetic material on the base and coaxial with and around the core and spaced therefrom, a movable coil around the core and each end thereof and adapted to oscillate about the axis of the core in the annular space between the conductor and core; a pair of strips each lying substantially along the axis of the core and normally in a common plane, each strip having one end portion secured to one prong and the other to the coil to provide a torsion suspension for the coil to oscillate about said axis; and a U member having the yoke thereof secured fast to the inner portion of the coil adjacent said end of the core and having arms projecting into the recess clear of the walls thereof and so near the walls that the arms prevent radial motion of the coil to a degree sufficient to prevent the coil from coming in contact with the core and conductor.

11. An instrument as claimed in claim 10 said flange

being provided with a radial slot, and said U member being elastic and normally having the end portions of the arms substantially perpendicular to the inner wall of the flange.

12. An instrument as claimed in claim 11 there being 5 two U members substantially back-to-back to each other.
